ELECTRICAL CONNECTION MEANS

Harry A. Douglas, Bronson, Mich., assignor to
 Kingston Products Corporation, a corporation
 of Indiana

Application March 6, 1936, Serial No. 67,474

17 Claims. (Cl. 173—328)

My invention relates to electrical connection means, and more particularly, to electrical connection means adapted for the reception of plug conductor terminals of the snap type. The principal object of my invention is to provide new and improved electrical connection means of these types.

Reference should be made to my copending application, Serial Number 57,620, filed January 4, 10 1936.

In the drawing accompanying this specification and forming a part of this application, I have shown, for purposes of illustration, several forms which my invention may assume, and in this 15 drawing:

Figure 1 is a perspective view of one embodiment of my invention.

Figure 2 is an enlarged longitudinal sectional view of the embodiment shown in Figure 1, with 20 certain parts shown in elevation, and showing in addition, in removed relation, a plug conductor terminal adapted for cooperation with the embodiment.

Figure 3 is an enlarged transverse section corresponding to the broken line 3—3 of Figure 2;

Figure 4 is a perspective view of the connecting means shown in Figures 2 and 3.

Figure 5 illustrates a blank from which the connecting means may be formed,

Figure 6 is a longitudinal sectional view of a 30 different embodiment of the invention, parts being shown in elevation,

Figure 7 is a perspective view of the embodiment shown in Figure 6, and showing the parts in 35 separated relation, and

Figure 8 is a longitudinal sectional view of a 40 different embodiment of the invention, parts being shown in elevation.

Referring particularly to Figures 1 through 5, 45 the embodiment of the invention disclosed therein comprises a receiving means designated generally by the reference numeral 10. The receiving means 10 comprises a supporting or housing means 11, formed of suitable electrical insulating material, and an electrical connector means 12.

The housing means 11 includes an elongated tubular member having an axial aperture 13, and 50 an integral tubular member having an aperture 14, the latter member being of lesser axial extent than the former member and being provided with a closed end 15 which merges with the elongated tubular member. As best shown in Figure 1, the end elevation of the two tubular members, or a transverse section therethrough, as shown in 55 dotted lines in Figure 3, generally resembles a

horizontally disposed figure eight. The apertures 13 and 14 are separated slightly to provide a wall 16 therebetween, and this wall is longitudinally slotted as shown at 17 so that the aperture 14, throughout its length, communicates with the 5 aperture 13. It will be noted that the walls of the slot 17 are generally opposite each other so as to provide for insertion of the connector means 12 to a position within the housing means 11, and also to hold the connecting means 12 against lateral displacement, although it will be appreciated that the walls of the apertures 13 and 14 also serve this latter purpose.

As shown in Figures 1 and 3, the outer walls of the tubular members generally conform to the 15 shape of the inner walls thereof, and at a point adjacent the closed end 15 of the aperture 14 the top and bottom walls (referring to Figure 3) of the housing means 11, intermediate the axes of the tubular members, are provided with transverse apertures 18, here shown to be rectangular in formation, and surrounding each of the apertures 18 is a boss 19, formed integral with the housing means 11.

The connector means 12 are preferably formed 25 from a single stamping, as shown in Figure 5, and of a suitable electric current conducting material. The stamping shown in Figure 5 comprises an elongated part 20, having, at its longitudinal extremities, integral portions projecting from the 30 longitudinal margins thereof. With reference to the disposition of the parts in Figure 5, the bottom longitudinal margin of the elongated part 20 is provided with downwardly extending portions 21 and 22 of generally the same length. The 35 margins of each of the portions 21 and 22 taper gradually, as shown at 23, toward the center of the respective portion, and adjacent the extremity of each portion 21 and 22, the margins taper 40 rather abruptly to a rounded point, as shown at 24. From the opposite longitudinal or upper margin of the elongated part 20 extend a portion 25 and a tongue 26, the portion 25 being aligned with the portion 22 but extending a greater distance away from the part 20. The portion 25 is 45 provided with generally parallel margins 27 extending from the part 20, the margins 27, at a point spaced from the part 20, tapering slightly, and a further point tapering rather abruptly to a rounded point, as shown at 28 and 29, the tapered 50 margins 28 and 29 being similar and generally equal in length to the tapered margins 23 and 24 of each of the portions 21 and 22.

The stamping, after being suitably formed, is shaped to conform to the shape best shown in 55

Figure 4. It will be noted that the portions 22 and 25 are formed to generally double ogee shape, with the abruptly tapered extremities 24 and 29 disposed adjacent to each other, and the portion 5 defined by the parallel margins 27 bent inwardly and disposed intermediate the loops formed by the portions 22 and 25. The portion 21 is bent similarly to the portion 22, and this portion forms a loop generally in axial alignment 10 with the loop formed by the portion 22. The elongated part 20 is also transversely curved to form a continuation of the curved surfaces of the loops formed by the portions 21 and 22. As best seen in Figure 3, the loops formed by the portions 15 21, 22, and 25, are generally circular in transverse section, and the abruptly tapered extremity of each portion is bent out of the locus of the circle and inwardly with respect to the respective loop.

The connector means 12 may be assembled 20 with the housing means 11 by sliding the loop formed by the portion 21 inwardly and from the right hand side (Figure 2) of the housing means 11. Means may be provided to properly position the connector means with respect to the housing means, and a suitable tool may be inserted 25 through one of the apertures 18 to bend the tongue 26 into the other of the apertures 18, as shown in Figure 3, to thereby securely hold the housing means 11 and connector means 12 in assembled position.

Plug conductors 30, two of which are shown in Figure 2, are adapted to cooperate with the loops formed by portions 21, 22, and 25, and these plug conductors comprise a generally cylindrical part 31 provided with an annular groove 32 and a tapered extremity 33. A conductor 34, 35 disposed within the plug conductor 30, may be secured thereto by swaging, as indicated by the swedge indentations 35.

40 Insertion of the plug conductor 30 into any one of the loops, for instance the loop formed by the portion 22, will cause the tapered extremity 33 of the plug conductor 30 to cam the extremity 24 of the portion 22 outwardly, to provide for the accommodation of the cylindrical part 31, and further insertion will cause the extremity 24 to snap into the annular groove 32 to thereby hold the plug conductor 30 in operative position. To remove the plug conductor 30, 50 a pull on the conductor will cause the surface of the annular groove 32 to cam outwardly the extremity 24, to provide for the removal of the cylindrical part 31 of the plug conductor 30.

Referring to Figures 6 and 7, the embodiment 55 therein disclosed comprises a supporting or housing means 36, formed of suitable insulating material, and a connector means 37 formed of suitable electric current conducting material.

The housing means 36 is provided with a generally cylindrical part 38 which merges with a tubular part 39, the latter part being of a width generally equal to the diameter of the cylindrical part 38, but being transversely elongated to a flattened horizontally disposed O-shape. 60 The tubular part 39 merges with the cylindrical part 38 intermediate the extremities of the housing means 36 by means of tapered wall portions as shown at 40.

The connector means 37 is preferably formed 70 from a single flat stamping somewhat similar to the stamping from which the connecting means 12 is formed. The stamping is subsequently formed to a shape best shown in Figure 7, to provide loops 41, 42, and 43 similar to the 75 loops formed by the portions 21, 22, and 25 of

the connecting means 12, but in this particular construction, the loops 42 and 43 are disposed on opposite sides of the axis of the loop 41. A body portion 44 connects the loop 41 with the loops 42 and 43, and a tongue 45 is formed intermediate the margins of the body portion 44, and intermediate the loop 41 and the loops 42 and 43.

The connector means 37 is assembled with the housing means 36 by inserting the loop 41 through the tubular part 39 and into the cylindrical part 38, and suitable means may be provided to properly align the connecting means 37 with respect to the housing means 36. As in the case of the embodiment shown in Figures 1 through 5, the housing means 36 is provided with oppositely disposed apertures 46, and the tongue 45 may be bent into operative position into one of the apertures by suitably manipulating a tool interposed through the other aperture. Lateral movement of the connecting means 37 with respect to the housing means 36 is limited by reason of the fact that the loops 42 and 43 closely fit within the inner surface of the tubular part 39. It will be understood that plug 20 conductors similar to the plug conductors 30 may be received and held within any one or all of the loops 41, 42, and 43 in a manner similar to that already described.

In Figure 8, a different embodiment is shown, 30 and this embodiment employs a plurality of connector means generally similar to the connector means 12 disclosed in the embodiment illustrated in Figures 1 through 5. As shown, two connector means 12a and 12b are provided, the connector means being respectively disposed in portions 48 and 49 of a housing means 50. Each of the portions 48 and 49 is generally similar to the housing means 11, and accommodates the respective connector means in a similar manner. 40 In this embodiment, however, it is preferred to make the loops on the connector means 12a somewhat smaller than the loops on the connector means 12b, so that plug conductors of one size may be inserted into the loops of the connector means 12a, and plug conductors of a different size may be inserted into the loops of the connector means 12b. In this manner, plug conductors intended for engagement with connector means 12a cannot inadvertently be 50 connected to connector means 12b. In some cases, however, it is desirable to make the loops of the connector means 12a and 12b of the same size so as to accommodate one particular size of plug conductor.

As shown, the connector means 12a and 12b are preferably disposed within the housing means 50 in oppositely disposed relation. In other words, the loop portions 21a and 21b of the respective connecting means are accessible from opposite sides of the housing means 50, and the connector means are insulated from each other by means of a partition 51, here shown to be integral with the housing means 50.

Each of the connecting means 12a and 12b 65 is held assembled with the housing means 50 by bending tongues 26a and 26b, formed respectively on the connector means 12a and 12b, into apertures 18a and 18b formed respectively in the portions 48 and 49 of the housing means 50. 70

With the construction shown in Figure 8, six conductors may be mechanically connected together, one conductor on one side of the housing means 50 being electrically connected to two on the other side.

From the foregoing it will be apparent to those skilled in the art that the illustrated embodiment of my invention provides a new and improved electrical connection means economical in construction and assembly, and accordingly, accomplishes at least the principal object of my invention. It further will be obvious to those skilled in the art that the illustrated embodiment of my invention may be variously changed and modified without departing from the spirit of my invention, or sacrificing all of the advantages thereof, and that accordingly, the disclosure herein is illustrative only, and my invention is not limited thereto.

15 I claim:

1. An electrical connecting device, comprising: a body, having a passage extending therethrough, said passage being formed to provide an enlarged part and a restricted cylindrical part; and a circuit continuing member, having spaced apart split cylindrical first means fitting in the enlarged part of the passage for simultaneously receiving a certain maximum number of conductor terminals, and having split cylindrical second means fitting in the restricted part for receiving a certain lesser maximum number of terminals; said means being spaced apart and independently operable of each other; said member being so constructed and arranged that said second means may be moved to position within said restricted part only by inserting said second means axially into said passage from the enlarged part of said passage.

2. An electrical connecting device, comprising: a body, having a passage extending through said body from end to end, and at least one recess, offset laterally from said passage; said recess extending inwardly from one end of said body, with a lateral recess portion communicating with the adjacent portion of said passage, and terminating intermediate the ends of said body; connector means for electrically connecting a plurality of conductor terminals, said connector means having two socket means unitary with each other and disposed in said passage to receive conductor terminals inserted into the ends of said passage respectively, and also having third socket means disposed in said recess to receive a conductor terminal inserted into the entrance end of said recess, said third socket means and one of said two socket means being spaced apart and so constructed and arranged that they are unitarily joined by a part disposed in said lateral recess portion, and said two socket means being each independently operable of said third socket means.

3. An electrical connecting device, comprising: a body, having a chamber having entrance openings at opposite ends of said body, one of said entrance openings being larger than the other, said larger entrance opening communicating with an enlarged part of said chamber and said other entrance opening communicating with a constricted part of said chamber; and a circuit continuing member having an enlarged part providing spaced apart split cylindrical receptacles disposed in said enlarged chamber portion and having a smaller part providing a split cylindrical receptacle disposed in said constricted part of said chamber; said receptacles of said enlarged part of said circuit continuing member being constructed and arranged to simultaneously receive a certain maximum number of conductor terminals inserted through said one entrance opening, and said receptacles of said smaller portion of

said circuit continuing member being constructed and arranged to receive and retain a conductor terminal independently of the enlarged part of the member.

4. An electrical connecting device, comprising: a body, having a passage extending therethrough, said passage being formed to provide an enlarged part and a restricted part; a circuit continuing member, having first means fitting in the enlarged part of the passage for receiving a certain maximum number of conductor terminals, and having second means fitting in the restricted part for receiving a certain lesser maximum number of terminals; said means being independently operable of each other abutment means provided on said body intermediate said enlarged part and said restricted part; and means provided on said circuit continuing member adjacent the inner extremities of said first and second means projecting into engagement with said abutment means whereby to lock said body and member in assembly.

5. An electrical connecting device, comprising: a body, having a passage extending therethrough, said passage being formed to provide an enlarged part and a restricted part; a circuit continuing member, having spaced apart independently operable split cylindrical first means fitting in the enlarged part of the passage for engaging a certain maximum number of conductor terminals, and having split cylindrical second means independently operable of said first means fitting in the restricted part for engaging a certain lesser maximum number of terminals; said member being so constructed and arranged that said second means may be moved to position within said restricted part only by inserting said second means into said body therewithin; abutment means within said body; and means provided on said continuing member adjacent the inner extremities of said first and second means engageable with said abutment means whereby to lock said body and member in assembly.

6. An electrical connecting device, comprising: a body, having a first chamber having entrance openings at opposite ends of said body, one of said entrance openings being larger than the other, said larger entrance opening communicating with an enlarged part of said chamber and said other entrance opening communicating with a constricted part of said chamber; a second chamber substantially parallel to and conversely of the first chamber having entrance openings at opposite ends of said body, one of said entrance openings being larger than the other, said larger entrance opening communicating with an enlarged part of said chamber and said other entrance opening communicating with a constricted part of said chamber; and a circuit continuing member insertable into either of said chambers and having an enlarged part disposed in one of said enlarged chamber portions and having a smaller part disposed in one of the constricted parts of said chamber, said enlarged part of said circuit continuing member being constructed and arranged to be engaged by a certain maximum number of conductor terminals inserted through one of said larger entrance openings, and said smaller portion of said circuit continuing member being constructed and arranged to be engaged by a certain lesser maximum number of conductor terminals adapted to be inserted through one of the smaller entrance openings.

7. An electrical connecting device, comprising: a body, having a chamber having entrance open-

- ings at opposite ends of said body one of said entrance openings being larger than the other, said larger entrance opening communicating with an enlarged part of said chamber and said other entrance opening communicating with a constricted part of said chamber; a circuit continuing member having an enlarged part providing independently operable receptacles disposed in said enlarged chamber portion and having a 5 smaller part providing a receptacle independently operable of the receptacles of said enlarged part disposed in said constricted part of said chamber, said enlarged part of said circuit continuing member being constructed and arranged to receive 10 a certain maximum number of conductor terminals inserted through said one entrance opening, and said smaller portion of said circuit continuing member being constructed and arranged to receive a certain lesser maximum number of conductor terminals inserted through said other entrance opening; abutment means on said body; and means associated with the inner extremities of said receptacles projecting from said continuing member engaging said abutment means 15 whereby to lock said member and said body together.
8. An electrical connecting device, comprising: a unitary circuit continuing member of sheet material, having means at one side for receiving a certain maximum number of plug conductor terminals of the snap-type, and having means at another side for receiving a certain different maximum number of plug conductor terminals of the snap-type; each of said receiving means being independently operable and having an entrance end and each having a part spaced from said entrance end, said part forming 20 detent means being constructed and arranged to resiliently engage a portion of the snap-type plug conductor terminal disposed therein, to mechanically and electrically hold the plug conductor terminal assembled with the receiving means.
9. An electrical connecting device, comprising: a unitary circuit continuing member of sheet material, having split cylindrical means at one side for receiving a certain maximum number of plug conductor terminals of the snap-type, and having split cylindrical means at another side for receiving a certain different maximum number of plug conductor terminals of the snap-type; each of said receiving means being independently operable and constructed and arranged to resiliently engage the terminal disposed therein, and 25 detent means associated with each receiving means adapted to engage a terminal assisting to retain same in said receiving means.
10. An electrical connecting device, comprising: a single piece of sheet-metal, having movable portions projecting in opposite directions from opposite margins, said projecting portions being bent inwardly toward each other, and being so constructed and arranged as to form a certain maximum number of conductor terminal receiving means at one end of said device, and a certain different maximum number of conductor terminal receiving means at the other end, each of said receiving means being independently operable and extending in parallel relation, and each 30 including detent means cooperable with said terminals.
11. An electrical connecting device, comprising: a sheet metal circuit continuing member, stamped into shape and so constructed and arranged that one end of said member provides a 35 certain maximum number of jack means and the other end of said member provides at least a pair of non-intersecting independently operable jack means; at least said pair of jack means being constructed and arranged to provide means to simultaneously receive and resiliently hold a pair of conductor terminals, and detent means on each of said pair of jack means cooperating with said terminals assisting to hold said terminals in said pair of jack means.
12. An electrical connecting device, comprising: an integral sheet metal circuit continuing member, stamped into shape and so constructed and arranged that one end of said member provides a certain maximum number of jack means and the other end of said member provides at least a pair of non-intersecting independently operable split cylindrical jack means; at least said pair of jack means being constructed and arranged to simultaneously receive and resiliently retain a pair of conductor terminals, and detent means associated with each of said jack means cooperating with said terminals.
13. An electrical connecting device, comprising: a sheet metal circuit continuing member rolled into shape to provide opposite end portions constructed and arranged to form axially aligned oppositely-disposed independently operable jack means, each constructed and arranged to receive and resiliently retain a conductor terminal inserted therein, said member having another portion constructed and arranged to form a third jack means adjacent one of said oppositely-disposed jack means, said third jack means and said adjacent jack means being non-intersecting and constructed and arranged each simultaneously to receive a conductor terminal.
14. An electrical connecting device consisting of two members: one being a body of insulating material provided with an opening; the other being a sheet metal circuit continuing member of generally C shape in cross section arranged in said opening, the extremities of the C providing non-intersecting receptacles each adapted to receive and resiliently retain a terminal; said body member having cooperating means; and the continuing member having an integral portion projecting outwardly from the back of the C in a direction opposite to its extremities into interlocking relation with said cooperating means whereby to permanently lock said members in assembly.
15. An electrical connecting device, comprising: an integral sheet metal circuit continuing member, stamped into shape and so constructed and arranged that one end of said member provides a certain maximum number of jack means and the other end of said member provides at least a pair of independently operable split cylindrical jack means; at least said pair of non-intersecting jack means being constructed and arranged to simultaneously receive and resiliently retain a pair of conductor terminals whereby said terminals will not intersect each other, and detent means associated with each of said jack means cooperating with said terminals; and means arranged centrally of said member whereby said member may be secured with respect to a support.
16. An electrical connecting device, comprising: a unitary circuit continuing member of sheet material, having split cylindrical means at one side for receiving a certain maximum number of plug conductor terminals of the snap-type, and having split cylindrical means at another side for

receiving a certain different maximum number of plug conductor terminals of the snap-type; each of said receiving means being independently operable and constructed and arranged to resiliently engage the terminal disposed therein; detent means associated with each receiving means adapted to engage a terminal assisting to retain same in said receiving means; and means for securing the member to a support arranged on said member remote from said cylindrical means.

17. An electrical connecting device, comprising: a single piece of sheet-metal, having movable portions projecting in opposite directions from opposite margins, said projecting portions being

bent inwardly toward each other, and being so constructed and arranged as to form a certain maximum number of conductor terminal receiving means at one end of said device, and a certain different maximum number of conductor terminal receiving means at the other end, each of said receiving means being independently operable and extending in parallel relation, and each including detent means cooperable with said terminals, and preformed means independent of said movable portions provided on said piece for attaching the piece to a support.

HARRY A. DOUGLAS.
